BOTTLE OR THE LIKE

Ron J. Klensch, Park Ridge, Ill., assignor to Tolibia Cheese, Inc., Chicago, Ill., a corporation of Wisconsin

Filed Dec. 9, 1968, Ser. No. 14,837

Term of patent 14 years

Int. Cl. D9—01

U.S. Cl. D9—131

FIG. 1 is a perspective view of a bottle showing my new design;

FIG. 2 is a cross-sectional view taken at the line 2—2 of FIG. 1;

FIG. 3 is a top view;

FIG. 4 is a bottom view; and

FIG. 5 is a fragmentary cross-sectional view through the top portion of a modified form of my new design, the remainder of the bottle not shown being the same in appearance as the bottle shown in FIGS. 1, 2, 3 and 4.

I claim:

The ornamental design for a bottle or the like, substantially as shown and described.
